UNITED STATES PATENT OFFICE.

WALTHER VOITH, OF ST. POLTEN, NEAR VIENNA, AUSTRIA.

WRITING DEVICE.

Application filed October 24, 1924, Serial No. 745,581, and in Austria October 31, 1923.

The device according to the present invention renders it possible to write manuscript notes of any kind on a writing surface without having to control the writing operation with the eye. The device is small-sized so that it can be carried in the pocket of the user, who with one finger of the hand thrust in the pocket is in a position to write unobserved short notes on a writing surface. The device also renders it possible to take short notes while walking or otherwise moving since the stylus is positively guided in a window of the device in which the writing surface is disposed so that the script occupies its correct position on the said surface in all circumstances.

A constructional example of the device according to the present invention is illustrated in the accompanying drawings in

which

Figure 1 is a partly sectional elevation,

Figure 2 is a plan and

Figure 3 is a vertical cross-section.

The lower portion of the casing 1 is closed by a removable plate or floor 2, the upper portion or cover of the said casing having a window 3 extending almost the whole length of the casing. The platen 4 is disposed below the window for writing purposes. A paper web or strip 5 is guided over the said platen and moves between a delivery roll 6 and a take-up roll 13, passing over guiding rolls 7, 8, 9, 10, 11 and 12. The paper web 5 moves together with an endless flexible band 14 of celluloid or the like, which is under the paper web on all guiding rolls, but over it on the take-up roll 13 and thence runs to the delivery roll 6 above the paper. The said band 14 forms a positive frictional connection between the rolls 6 and 13 so that the delivery of the paper strip from the roll 6 and the take-up thereof on the roll 13 are uniform.

The paper web must always be taut and for this purpose the rolls 7 and 8 are mounted on bars pivoted to links 16 adapted to oscillate about the axis of the roll 9 and pressed against the roll 6 by a spring 17. The free end of the bar 15 lies in a stationary guiding slot 18. It will be clearly seen that the band 14, which surrounds in a large circle the coil of paper on the roll 6, is always held taut by the spring 17 and exerts frictional pressure upon the paper.

The rolls 11 and 12 are similarly mounted on bars 19 articulated to links 20 oscillable

about the axis of the roll 10 and pressed against a roll 13 by the spring 21, the free end of the bars 19 lying in a guiding slot 22. The guiding rolls must be resiliently mounted because the diameter of the paper supply rolls 6 decreases as the paper is used while the diameter of the coil of paper on the roll 13 proportionately increases. The band 14 being always taut and always in frictional engagement with the web of paper 5, the latter can be regularly wound on or off by seizing the said web or the band at a certain point and shifting it.

The two longitudinal edges of the window 3 have guides 23 in which a runner 24 is adapted to move longitudinally to the window. The runner has a slot 25 lying transversely to the direction of motion of the said runner. A slide 26 is guided in the slot and carries a locking sleeve 27 on which the stylus is supported, the sleeve being movable in the slide 26 in a direction at right angles to the strip of paper. The sleeve 27 has a flange 28 against which abuts one end of a spring 29, the other end thereof abutting on a hollowed-out knob 30 screwed to the upper end of a cylinder 31 of the slide 26. Two arms 32 fitted to the sleeve 27 project through slots cut on the said cylinder 31. The spring 29 weighs on the sleeve 27 downwards so that the point of the stylus is pressed upon the paper strip 5 to a sufficient extent to leave marks on the paper when moved thereon, without it being necessary to press the stylus downwards with the finger. The stylus may of course be fitted with a spring whereby it is normally held away from the writing surface, a downward pressure being exerted upon the arms 32 or any other element for writing purposes.

When it is desired to write on the portion of the paper web lying within the compass of the window 3, the runner 24 is first moved to the left-hand side end of the window, whereafter the first or any other finger is placed in the hollowed-out portion of the knob 30 for the purpose of moving the stylus and put script down on the paper. To this end, the runner 24 moves longitudinally to the window and the stylus moves in the guide 25 transversely to the said window. These two movements may be combined into any other movement. The stylus being moved longitudinally and transversely is compelled to remain within the direction of the line longitudinally to the window. It

is thus possible to write from the left end to the right end of the window until the stylus comes into contact with the right-hand side edge of the window. This directs 5 the attention of the writer upon the fact that the paper strip must now be fed forward. To this end, the two end edges 33 and 34 of the window 3 are each provided at their centre with a notch 35 and 36 respectively adapted to receive the stylus holder. After coming into contact with the edge 34, the stylus is slightly moved in the slot 25 in one or the other direction until it engages the notch 36, this being quite easily felt. 15 Holes 37 are provided on the band 14 at intervals corresponding to the length of the window 3. Moreover, the platen 4 is cut out along the longitudinal central-line of the window, the construction now described having 20 a groove 38. The arms 32 are depressed when the stylus is in the notch 36 on the right-hand side of the window 3, with the consequence that the said stylus perforates the paper and engages a hole 37 provided on 25 the band 14 under the notch 36. The various elements being in this position, the runner 24 is moved to the left-hand side end of the window 3, the stylus pulling along the paper strip and the band 14, the latter rotating the 30 rolls 6 and 13 so that the strip of paper is wound off the roll 6 onto the roll 13. The stylus is now disengaged by means of the arms 32 from the holes in the paper strip and in the band, whereafter writing may be 35 resumed and continued until the stylus has again reached the right-hand side end of the window, the strip of paper being then once more fed along as described. The paper may be fed merely by feeling with the 40 operating finger and without having to look at the device.

The available supply of blank paper is ascertained by passing a finger through an inspection window 39 cut in the plate 2 in 45 the vicinity of the roll 6. The device may be rendered inoperative by removing the slide 24 and the runner 26 and placing them within the casing after removal of the plate 2.

50 The supply of paper is renewed by taking the rolls 6 and 13 out of the casing and placing a fresh coil of blank paper on the roll 6. The strip of paper is now passed over the guiding rolls and its end is secured 55 to the roll 13, the coil of used paper being now taken down, the script thereon may be read with ease. If however it is desired to read a note while the web of paper is still within the device (that is to say when it is 60 not yet fully used) the said web may be moved backwards, either by directly seizing it or by means of the stylus, until the desired portion of the web shows through the window.

65 The constructional details of the device

just described may of course be altered in many ways, more particularly as regards the means for guiding the strip of paper and the friction connection between the delivery and take-up rolls. The stylus guiding means may also be modified and, as stated in the foregoing, the stylus may be normally held away from the writing surface and may be pressed thereon for writing purposes. The paper strip runs no risk of being accidentally perforated because it is supported on the band 14 throughout the length of the window and also over the groove 38. The said strip may be perforated only at the right-hand side end of the window, this being of course intentional. Also the strip of paper may be fed by other means than those described, for example by rotating the roll 13 in any desired way. Furthermore a feeler could be in contact with the coil of 85 paper on the roll 6, the said feeler touching a projection when the supply of paper is exhausted so that the attention of the user is directed to the necessity of placing a fresh supply of paper in the device by the fact 90 that he cannot operate the feed mechanism. Finally, the writing surface may be moved parallel to the narrow edge of the window, the script being disposed in this case in parallel lines. 95

What I claim as my invention and desire to secure by Letters Patent is:

1. In a device comprising a casing, a window therein, and a strip for a manuscript under said window, said strip being guided within said casing, the combination of a runner arranged above said window, means for guiding said runner longitudinally to said window, a slide guided upon said runner transversely of its longitudinal movement, and a sleeve, said sleeve carrying a stylus, said sleeve being supported by said slide, said sleeve being movable perpendicularly to said strip, a spring tending to move said sleeve away from said strip, and a knob fixed to said sleeve, said sleeve being movable in all directions parallel to said strip while being pressed against it. 100

2. In a device comprising a casing, a window therein, and a strip for a manuscript under said window and guided within said casing, the combination of a runner arranged above said window, means for guiding the runner longitudinally to said window, a slide guided upon said runner transversely of its longitudinal movement, and a sleeve, said sleeve carrying a stylus, said sleeve being supported by said slide, said sleeve being movable perpendicularly to said strip, a knob fixed to said sleeve, said knob serving as a bearing for a finger of the person using the device, whereby said sleeve carrying said stylus can be pressed down when writing, and grips on said sleeve for lifting the sleeve away from the strip when said 115 120 125 130

strip is moved to bring a fresh manuscript surface into the window of the casing.

3. In a device comprising a casing, a window therein, and a strip for a manuscript under said window and guided within said casing, the combination of a runner arranged above said window, means for guiding said runner longitudinally to said window, a slide guided upon said runner transversely 10 of its longitudinal movement, a sleeve, said sleeve supporting a stylus, said sleeve being supported by said slide, said sleeve being movable perpendicularly to said strip, a knob fixed to said sleeve, said knob serving as a bearing for a finger of the person using the device for pressing down the sleeve together with the stylus, and a flexible band passing beneath said strip and being guided together with it by 15 said casing, said band being provided at distances equal to the length of the window of the casing with holes, said holes being of such a size that said stylus may be inserted therein.
- 20 4. In a device comprising a casing, a window therein, and a strip for a manuscript beneath said window and guided within said casing, the combination of a runner arranged above said window, means for guiding said

runner longitudinally to the window, a slide 30 guided upon said runner transversely of its longitudinal movement, a sleeve, said sleeve carrying a stylus and being supported by said slide, said sleeve being movable perpendicularly to said strip, a knob fixed to 35 said sleeve, said knob serving as a bearing for a finger of the person using the device for pressing down the sleeve together with the stylus, and a flexible band passing beneath said strip and being guided together 40 with it, said band being provided at distances equal to the length of said window with holes, said holes being of such a size that the stylus may be pushed therein each of the end edges of said window being provided with a 45 notch.

5. In a device as set forth in claim 4, the combination of said sleeve with grips fixed on said sleeve for lifting said sleeve together with said stylus away from said strip. 50

6. In a device as set forth in claim 4, a platen arranged within said casing below said window and serving as a support for said strip and said flexible band, said platen having a groove extending in the direction 55 of the movement of said strip.

In testimony whereof I affix my signature.
WALTHER VOITH.
